UNITED STATES PATENT OFFICE.

EDWARD W. VAILL, OF WORCESTER, MASSACHUSETTS.

FURNITURE.

SPECIFICATION forming part of Letters Patent No. 289,583, dated December 4, 1883.

Application filed June 19, 1883. (No model.)

To all whom it may concern:

Be it known that I, EDWARD W. VAILL, of Worcester, in the State of Massachusetts, have invented an Improvement in Furniture, of 5 which the following is a specification.

The surfaces of chairs, sofas, and other articles of furniture have been ornamented by inlaid veneers, pearl, straw, and metal. These are all difficult to apply and have to be put 10 into the wood-work when the article is being made. In cases where the frames are upholstered in a material different to that originally intended, there is no opportunity to alter the ornamental surface to harmonize with the up- 15 holstery.

My present invention is for the purpose of ornamenting the surface of the article of furniture in a manner that admits of a great variety of combinations of color and artistic 20 effect, and which can be applied either before or after the furniture is upholstered, so as to harmonize the colors and the appearance. I 25 recess the surface of the article of furniture in strips, bands, or other forms, each recess being about one-tenth of an inch deep, more or less, and preferably with sharp angles at the junction of the bottom and sides of the recesses. The exterior surfaces of the wooden 30 frames, rails, or panels are to be varnished, stained, polished, or otherwise finished up to suit the style or the taste of the person making the same, and the recessed portion may be left free from varnish, especially on the bottom. Into these recessed portions I introduce a 35 woven piled fabric—such as plush, velvet, cut or uncut Brussels carpet, tapestry, or similar fabric—the same being of a shape to fit closely into such recesses, the back or foundation of the fabric being covered at its edges in consequence of being within the recesses, and the 40 piled surface is even with or projects beyond the surface of the surrounding wood.

In the accompanying drawings, Figure 1 is a section, and Fig. 2 a face view, of part of a

chair-back with my improvement applied 45 thereto, *a* being the wood, the surface of which is recessed, and receives the woven portion or backing *b*, from which the piled or plush surface *c* projects, and forms the contrasting material to the surrounding wood-work, the carpet, plush, or piled fabric being inlaid in the wood. The carpet or fabric may be secured by glue or any suitable adhesive material, and ornamental nails, as at *i*, may also be made use of in holding the fabric into 50 its recess.

In some instances I undercut or dovetail the recesses, so as to hold the edges of the carpet, or the carpet may be held in any suitable manner. I am able to utilize small pieces 60 of carpet and plush that would otherwise be wasted, and to intersperse various patterns and colors throughout the wood-work, and the same forms a very agreeable and artistic contrast to the surrounding surface. 65

I claim as my invention—

1. The combination, with the wood-work in furniture, of piled woven fabrics introduced into recesses in the surface of the article, substantially as set forth. 70

2. A frame or other wooden article of furniture having recesses in the surface thereof, in combination with strips or pieces of plush or other woven textile fabric inserted into such recesses and secured by glue or otherwise, substantially as set forth. 75

3. The plush or other piled fabric, in combination with the recessed surface of furniture and glue or nails, or both, for securing such plush fabric into the recessed wood-work, substantially as set forth. 80

Signed by me this 12th day of June, A. D. 1883.

E. W. VAILL.
